United States Patent Office

Des. 184,756
Patented Mar. 31, 1959

184,756

BEVERAGE CART OR SIMILAR ARTICLE

Victor D. Molitor, Englewood, Colo.

Application February 17, 1958, Serial No. 49,682

Term of patent 14 years

(Cl. D14—3)

FIG. 1.

FIG. 2.

Fig. 1 is a front perspective view of a beverage cart embodying my new design; and

Fig. 2 is a rear perspective view of the beverage cart of Fig. 1.

The essential features of my design are shown in full lines.

I claim:

The ornamental design for a beverage cart or similar article, as shown and described.
